Primary Examiner — Messina L Smith

(57) **CLAIM**

The ornamental design for a toaster, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a front, top, right side perspective view of a toaster showing the new design;

FIG. 1.2 is an exploded view of the toaster;

FIG. 1.3 is rear view of the toaster;

FIG. 1.4 is a front view thereof;

FIG. 1.5 is a bottom view thereof;

FIG. 1.6 is a right side view thereof;

FIG. 1.7 is a top view thereof;

FIG. 1.8 is a left side view thereof; and

FIG. 1.9 is a rear, right side perspective view thereof.

In the drawings, the portions being overlaid by the red, transparent tone form no part of the claimed design.

**1 Claim, 9 Drawing Sheets
(9 of 9 Drawing Sheet(s) Filed in Color)**
